COMB WITH INTERCHANGEABLE TEETH

Fannie Price, New York, N. Y.

Application September 18, 1946, Serial No. 697,726

9 Claims. (Cl. 132—16)

1

This invention relates to combs, brushes and the like and more particularly to combs of the variety having removable teeth so that when they become worn or broken they can be replaced with new teeth.

It is an object of the present invention to provide a handle and rod arrangement for a comb having removable teeth wherein the teeth can be removed from the rod at the end thereof removed from the handle and without having to remove the handle therefrom and by simply releasing the handle from the rod.

It is another object of the invention to provide a comb structure of a type having removable teeth elements which can be fitted into a brush body without incurring or consuming great space or requiring that the body portion of the brush be enlarged.

According to the invention, a handle contains a rod and means for adjusting the rod relative to the handle. Teeth elements are disposed on the rod opposite to the handle end thereof and means is provided whereby the teeth elements will be retained against removal from the rod. This means is an end formation from which the rod is released or in another form of the invention an end formation which is removable from the rod end. In both forms, the teeth elements are removed from the rod at the end thereof removed from the handle.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a side elevational view of a combined brush and comb with the teeth in place and ready for use.

Fig. 2 is a transverse cross sectional view taken along the line 2—2 of Fig. 1 looking in the direction of the arrows thereof.

Fig. 3 is a longitudinal cross sectional view taken generally along the line 3—3 of Fig. 2 looking in the direction of the arrows thereof.

Fig. 4 is a fragmentary longitudinal cross sectional view of the brush end of the device when the rod has been slightly withdrawn to permit either the removal or the addition of tooth elements.

Fig. 5 is an elevational view of a modified form of comb having means for permitting the removal

2

of the tooth elements from the end of the rod remote from the handle.

Fig. 6 is a detail perspective view of the rod removed from the handle which serves to retain the teeth.

Fig. 7 is a detail perspective view of one of the end formations between which the teeth are retained on the rod.

Fig. 8 is a perspective view of the opposite end formation having means for securing the same to the rod after having been turned through an angle.

Fig. 9 is a cross sectional view taken through the end formation shown in Fig. 8 as along line 9—9 looking in the direction of the arrows thereof.

Fig. 10 is a cross sectional view taken through the comb as shown in Fig. 5 along the line 10—10 thereof looking in the direction of its arrows.

Fig. 11 is a longitudinal cross sectional view of the comb shown in Fig. 5.

Fig. 12 is a detail perspective view of an individual tooth element such as used with both forms of the invention.

Referring now to the figures, 21 represents a combined brush and comb comprising a brush and comb handle 22 having a body portion 23 integral therewith. Brush clusters 23' are secured to the body portion 23. The handle portion 21 has a hole 24 extending therethrough and in communication with a slot 25 extending upwardly

from the bottom face of the body portion and throughout substantially its full length except for an end formation 26 serving as a stop for tooth elements 27 (Fig. 12) adapted to be disposed in the slot 25. Extending through the hole 24 is a tooth-retaining rod 28. This rod extends into and throughout the length of the body recess 25 and for that portion of the rod which extends within the recess 25 it has a longitudinally-extending guide 29 which cooperates with key way

slots 31 of the tooth elements 27 whereby to retain the tooth when upon the rod against rotation and disalignment with respect to one another. The end of the rod 28 when in its retaining position extends into a recess or depression 32 of the same section as the rod whereby to prevent the rotation of the rod relative to the body portion 23.

The opposite end of the recess 25 has a slot 33 for receiving the opposite end of guide 29 and serves also to prevent rotation of the rod 28. The guide 29 is slidable in the slot 33 as the rod 28 is axially adjusted to release or receive tooth elements.

The handle 21 has an internally threaded fer-

rule 34 embedded therewithin adapted to receive a slit externally threaded sleeve 35 adapted to rotate in an annular recess 36 on the rod 28. Since the ferrule 34 is fixed to the handle any rotation of the sleeve 35 therewithin will effect axial adjustment of the sleeve and of the rod 28 within the handle and body portions. The sleeve 35 may have a radially-extending flange 37, and a cap 39 with a screw driver slot 40 can be secured over the end face thereof by rivets 41. This cap 39 receives the end of the rod 28.

As the sleeve 35 is turned through the agency of the cap 39 the rod 28 will be withdrawn from the recess 32 of the body end 26 as illustrated in Fig. 4. This is sufficient to permit the removal of the teeth 27 for replacement or cleaning. When the full number of tooth elements have been added to the rod the sleeve 35 can be rotated in the opposite direction and the rod end returned to the recess 32 to secure the tooth elements in place upon the rod. A spring washer 42 can be disposed on the rod to make certain that the recess is filled throughout its length with tooth elements and to prevent any slight looseness between tooth elements.

Referring now to the form of the invention shown in Figs. 5 to 12, 45 represents a rod having a threaded end 46 and a tooth element receiving portion 47 with a guide 48 extending longitudinally therethrough. The guide 48 terminates short of end 49 of the rod. On the end 49 are pins 51, only one being shown, but the same being diametrically opposite one another on the rod over which an end formation 52 is slid for engagement with the rod. This end formation has a hole 53 therein for receiving the rod end and slots 54 for receiving the pin projections 51. The slots 54 extend to an annular recess 55 which will permit the end formation to be rotated so that the slots 54 are out of registry with the pin 51 and whereby the end formation can be retained on the rod against axial displacement.

Adjacent the threaded end of the rod 45 is a handle sleeve 56 having a ferrule 57 on its inner end for engagement with a tooth element stop 58, which is recessed at 59 to receive one end of guide 48. On the threaded end 46 is a threaded sleeve 61 having a head portion 62 for turning the same and for causing, as the sleeve is turned, the tightening of the end formation 52 against teeth elements 27 disposed upon the rod 45. The handle 56 is axially slidably mounted on its respective end of the rod 45; and the sleeve 61 of the head portion 62 is rotatively received in a complementary recess formed in the outer end of the handle 56.

If it is desired to remove teeth elements 27 from the portion 47 of the rod, the sleeve 61 is loosened to release the end formation 52. The end formation 52 is turned upon the rod so that its recesses 54 register with the pins 51 and the end formation 52 is then axially removed from the rod. The pins 51 should then be removed to permit the removal of the tooth elements 27. To assemble the tooth elements and make the comb rigid, the operation is reversed.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A comb, comprising a rod having a guide extending along one side of a portion thereof, a handle on the remaining portion of said rod, individual tooth elements engaged on the end of said rod formed with said guide, said tooth elements being formed with key way slots engaged by said guide to prevent rotation of said tooth elements on said rod, an end formation engageable with the free end of said rod, and means on said handle cooperative with the adjacent end of said rod for moving the rod axially of said handle to hold the tooth elements in position on said rod between said end formation and the inner end of said handle.

15 2. A comb, comprising a rod having a guide extending along one side of a portion thereof, a handle on the remaining portion of said rod, individual tooth elements engaged on the end of said rod formed with said guide, said tooth elements being formed with key way slots engaged by said guide to prevent rotation of said tooth elements on said rod, an end formation engageable with the free end of said rod, and means on said handle cooperative with the adjacent end of said rod for moving the rod axially of said handle to hold the tooth elements in position on said rod between said end formation and the inner end of said handle, said end formation comprising a body portion formed integrally with said handle and extended the length of said tooth elements and having an end wall projected across the free end of said rod, said end wall being formed with a recess for receiving the free end of the rod when moved axially to confine the end of the said rod and prevent removal of the tooth elements from said rod.

30 3. A comb, comprising a rod having a guide extending along one side of a portion thereof, a handle on the remaining portion of said rod, individual tooth elements engaged on the end of said rod formed with said guide, said tooth elements being formed with key way slots engaged by said guide to prevent rotation of said tooth elements on said rod, and end formation engageable with the free end of said rod, and means on said handle cooperative with the adjacent end of said rod for moving the rod axially of said handle to hold the tooth elements in position on said rod between said end formation and the inner end of said handle, said end formation comprising a body portion formed integrally with said handle and extended the length of said tooth elements and having an end wall projected across the free end of said rod, said end wall being formed with a recess for receiving the free end of the rod when moved axially to confine the end of said rod and prevent removal of the tooth elements from said rod, said recess being of a cross-sectional shape corresponding to the cross-sectional shape of said rod and its guide, whereby engagement of the end of said rod into said recess will hold the rod against rotation.

35 4. A comb, comprising a rod having a guide extending along one side of a portion thereof, a handle on the remaining portion of said rod, individual tooth elements engaged on the end of said rod formed with said guide, said tooth elements being formed with key way slots engaged by said guide to prevent rotation of said tooth elements on said rod, an end formation engageable with the free end of said rod, and means on said handle cooperative with the adjacent end of said rod for moving the rod axially of said handle to hold the tooth elements in position on said rod between said end formation and the

inner end of said handle, said end formation comprising a body portion integrally formed with said handle, said body portion being formed with a longitudinal slot housing the portion of said rod formed with said guide and the ends of said tooth elements engaged on the said portion of said rod, an end wall closing the end of said slot at the outer end of said body portion, said end wall being formed with a recess of a cross-sectional shape corresponding to the cross-sectional shape of said rod and its guide for non-rotatively receiving the end of said rod when moved axially to cover the end of said rod and prevent removal of the tooth elements from said rod.

5. A comb, comprising a rod having a guide extending along one side of a portion thereof, a handle on the remaining portion of said rod, individual tooth elements engaged on the end of said rod formed with said guide, said tooth elements being formed with key way slots engaged by said guide to prevent rotation of said tooth elements on said rod, an end formation engageable with the free end of said rod, and means on said handle cooperative with the adjacent end of said rod for moving the rod axially of said handle to hold the tooth elements in position on said rod between said end formation and the inner end of said handle, said end formation comprising a body portion integrally formed with said handle, said body portion being formed with a longitudinal slot housing the portion of said rod formed with said guide and the ends of said tooth elements engaged on the said portion of said rod, an end wall closing the end of said slot at the outer end of said body portion, said end wall being formed with a recess of a cross-sectional shape corresponding to the cross-sectional shape of said rod and its guide for non-rotatively receiving the end of said rod when moved axially to cover the end of said rod and prevent removal of the tooth elements from said rod, said handle being formed in its end from which said body portion extends with a slot for longitudinally slidably receiving the adjacent end of said guide to assist in retaining the rod against rotation.

6. A comb, comprising a rod having a guide extending along one side of a portion thereof, a handle axially slidably mounted on the remaining portion of said rod, individual tooth elements engaged on the end of said rod formed with said guide, said tooth elements being formed with key way slots engaged by said guide to prevent rotation of said tooth elements on said rod, an end formation engageable with the end of the rod adjacent the endmost tooth element remote from said handle, and means on said handle cooperative with the other end of said rod for moving the rod axially of said handle to hold the tooth elements in position on said rod between said end formation and the inner end of said handle, said moving means comprising a sleeve rotatively mounted on the said other end of said rod, the outer end of said handle being formed with a threaded annular recess of a diameter to receive said sleeve, threads formed on the outer periphery of said sleeve engaging the threads of said recess, and an outwardly directed flange formed on the outer end of said sleeve and abutting the outer end of said handle for moving the rod longitudinally as the sleeve is turned relative to said handle.

7. A comb, comprising a rod having a guide extending along one side of a portion thereof, a handle axially slidably mounted on the remain-

ing portion of said rod, individual tooth elements engaged on the end of said rod formed with said guide, said tooth elements being formed with key way slots engaged by said guide to prevent rotation of said tooth elements on said rod, an end formation engageable with the end of the rod adjacent the endmost tooth element remote from said handle, and means on said handle cooperative with the other end of said rod for moving the rod axially of said handle to hold the tooth elements in position on said rod between said end formation and the inner end of said handle, said guide being extended to a point short of the free end of said rod, a projection extending radially from the end of said rod engaged by said end formation, said end formation being formed with a recess for receiving the said first end of said rod and a slot extended radially from said recess for receiving said projection, said end formation also being formed with an internal annular recess concentric with said first recess and in communication with said first recess and said slot, said annular recess being at a location to receive said projection when the end formation is turned relative to said rod with said rod extended fully into said first recess so as to retain said end formation in position of said rod.

8. A comb, comprising a rod having a guide extending along one side of a portion thereof, a handle on the remaining portion of said rod, individual tooth elements engaged on the end of said rod formed with said guide, said tooth elements being formed with key way slots engaged by said guide to prevent rotation of said tooth elements on said rod, and end formation engageable with the free end of said rod, and means on said handle cooperative with the adjacent end of said rod for moving the rod axially of said handle to hold the tooth elements in position on said rod between said end formation and the inner end of said handle, said guide being extended to a point short of the free end of said rod, a projection extending from the free end of said rod, said end formation being formed with a recess for receiving the free end of said rod and a slot extended radially from said recess for receiving said projection, said end formation also being formed with an internal annular recess concentric with said first recess and in communication with said first recess and said slot, said annular recess being at a location to receive said projection when the end formation is turned relative to said rod with said rod extended fully into said first recess so as to retain said end formation in position of said rod, said end of said rod being formed with two of said projections extended from diametrically opposite sides thereof and said end formation being formed with two slots extended from diametrically opposite sides of said first recess for receiving said projections.

9. A comb, comprising a rod having a guide extending along one side of a portion thereof, a handle on the remaining portion of said rod, individual tooth elements engaged on the end of said rod formed with said guide, said tooth elements being formed with key way slots engaged by said guide to prevent rotation of said tooth elements on said rod, an end formation engageable with the free end of said rod, and means on said handle cooperative with the adjacent end of said rod for moving the rod axially of said handle to hold the tooth elements in position on said rod between said end formation and the inner end of said handle, said moving means com-

prising a recess formed in the free end of said handle, threads formed on the free end of said rod within said recess, and a head portion rotatively received in said recess and formed with an internally threaded passage for the threaded end of said rod, whereby rotation of said head portion relative to said handle will move said rod longitudinally. 5
